UNITED STATES PATENT OFFICE.

CYRUS W. LLOYD, OF SALISBURY, MARYLAND, ASSIGNOR TO W. A. WARRINGTON & CO., OF SAME PLACE.

FRUIT-CRATE.

SPECIFICATION forming part of Letters Patent No. 335,369, dated February 2, 1886.

Application filed November 2, 1885. Serial No. 181,681. (No model.)

To all whom it may concern:

Be it known that I, CYRUS W. LLOYD, of Salisbury, in the county of Wicomico and State of Maryland, have invented a new and 5 useful Improvement in Fruit-Crates, of which the following is a description.

Figure 1 is a side elevation of the crate. Fig. 2 is a vertical transverse section of one side of the crate, through line *x x* of Fig. 1; and 10 Fig. 3 is a horizontal section of the same through line *y y*.

In the construction of fruit-crates the ordinary method of fastening together the vertical and horizontal strips is to nail them, 15 simply. It frequently happens with this form of connection that, when the crates are pitched from the car, upon striking on the corner at the end they will mash or the nailed sections will turn upon each other.

20 My improvement consists in gaining or cutting the vertical strips of both the end and side panels and fitting the horizontal strips into said gains, and extending the ends of one set of panels out flush with the outer sides of 25 the vertical strips of the other side panels, and fastening them by metal angle-irons, as hereinafter described, whereby a crate of much stiffer sides and stronger corners is produced, which effectually resists the rough 30 handling and diagonal strain.

In the drawings, A represents a crate made of vertical strips B B' and horizontal strips C C'. The vertical strips are gained or halved with a recess just the width of the horizontal 35 strips, and into these recesses are fitted said horizontal strips and there secured by a single nail, which forms a stiff and secure joint that will not permit the parts to turn upon each other, and which, in consequence, makes 40 a crate that is very strong in resisting oblique strains.

In order to cut the gains or recesses cheaply, smoothly, and rapidly, the lumber is run lat-

erally through a machine having revolving cutters, which cut transversely to the lumber 45 the gains or grooves, the cutters being gaged to cut to the right depth, and thus doing the work continuously and quickly. After the vertical strips B of the side panels are secured to the horizontal strips C, and the 50 vertical strips B' of the end panels are fastened to the horizontal strips C', the end panels are fitted to the side panels with their outer edges flush with the outer faces of the side strips, B, and are there secured by 55 nailing and angle-irons *a*, the horizontal strips being on the inside of the vertical strips at both ends and sides. This it will be seen makes a very solid corner of double thickness, with the horizontal end strips, C', firmly 60 locked in place between vertical strips B and B', and with all of the joints of the crate lock-joints by reason of the gains.

Instead of putting the ends of the end panels flush with the sides of the side panels, as 65 shown, substantially the same result can be obtained by putting the ends of the side panels flush with the side of the end panels.

I am aware of Patents Nos. 85,226, 163,971, and 136,968, and do not claim anything shown 70 therein.

Having thus described my invention, what I claim as new is—

A crate having its horizontal strips C of the side panels let into the vertical strips B 75 of said side panels, and its horizontal strips C' of the end panels let into the strips B' of said end panels, and its two sets of panels fastened together with the ends of one set flush with the outer sides of the other, and angle- 80 irons *a* for securing them, substantially as shown and described.

CYRUS W. LLOYD.
